ANTIRATTLER DEVICE FOR WINDOWS AND
THE LIKE

Elio V. Francescon, Boston, Mass.

Application March 17, 1937, Serial No. 131,426

3 Claims. (Cl. 292—76)

This invention relates to a device to prevent rattling or involuntary motion of windows and the like.

I am well aware that anti-rattler devices for this purpose have been made by others, and it is one object of my invention to provide a superior device of this type, which is always reliable when once fixed in position for use. Other devices slip sidewise and ultimately fall out of their place between the window sash and the window jamb because of this side slippage, and it has been a particular object to provide a device that overcomes this fault. Another object is to make a device together with means to fasten it in place at both ends, in a single unit from an integral piece of material. Recognizing that such devices must be sold for a small sum it has been my object to create one of such simple construction that it can be economically produced on a quantity production basis, and, therefore, meet the price competition of inferior devices of this type and can be placed in position for use between the window sash and jamb by one simple and obvious operation.

The foregoing and other objects which will appear as the nature of the invention is better understood, may be accomplished by a construction and arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

35 In the drawing:

Figure 1 is a front elevational view showing my device, by dotted lines, in its position between a window sash and a window jamb viewed from inside a house or building, in which position it will prevent rattling or involuntary motion of the window.

Figure 2 is a sectional view taken on the line 2—2 of Figure 1.

Figure 3 is a perspective view of my anti-rattler device.

Figure 4 is a sectional view of an end portion of my device taken on the line 4—4 of Figure 3.

Figure 5 is a sectional view of my device taken on the line 5—5 of Figure 3.

Figure 6 is a bottom view of my device, broken away, showing an end portion viewed from the under side.

I have illustrated a portion of a window pane 12, set in a window sash 13 which has a front or inner face 14 as viewed from inside a room where

the window is. The window jamb or frame 15 in which the window is movably mounted and which embodies the usual retaining strip, has an inner face 16 which is adjacent said inner face 14. Between said window sash 13 and said window jamb 15 my anti-rattler device 17 is mounted, preferably clinging to the said front face 14 of said window sash 13 and bearing against the inner face 16 of the window jamb 15, whereby it serves as a filler in the space between the said window jamb and window sash, and prevents any rattling movement of said window sash.

As will be noted from Figure 1 of the drawing said device 17 is so relatively small that it is out of sight when in position, being obscured from view by said window jamb 15. The mounting of my device 17 could be reversed, of course, to have it cling to the said window jamb inner face 16.

Said anti-rattler device is made in one piece, 20 preferably of metal spring material, consisting of a main body portion 18 which protrudes or bows outwardly thereby resiliently bearing against said window jamb inner face 16, as shown in Figures 2 and 3 of the drawing. Said body portion 18 will 25 yield or move sufficiently to permit sliding of the window up or down; and it takes up the normal play space between the window sash and window jamb and thereby prevents rattling.

At each end of my device 17 and integral therewith securing means are formed consisting of spurs 19 on each side thereof, the material forming said device 17 being turned downwardly and extending inwardly, as illustrated in the drawing, said spurs 19 being inset from the outside 35 edges of my said device 17. Said spurs 19 penetrate into the wood of said window sash 13 and my device clings to its position thereon. It is a feature of my invention to form said spurs 19 so that they are inset from the outside edges of my 40 device 17, thereby eliminating practically all possibility of having it fall from its position on said window sash by an outside corner thereof striking against said window jamb as the window is moved, which will occasionally happen if the said 45 spurs 19 are not inset, as shown. To more permanently secure my device 17 in position I provide spur means 22 at the end which are preferably made double as shown, and which are located intermediate said spurs 19, being integral with 50 said device 17. These intermediate spurs 22 likewise protrude into said window sash 13 and are so shaped that they slant diagonally downward from the said body portion 18 to the end as at 23, forming a sharp corner, as best illustrated in Figure 5 55

of the drawing. Inasmuch as a window will be slid up and down hundreds or thousands of times, said spurs 22 are an important feature of my invention, reinforcing, as they do, the grip of said outer spurs 19. Inasmuch as vertical movement of the window temporarily flattens out the body of my device 17 somewhat, said spurs 19 and 22 move slightly in the paths they cut in the window sash 13 as the window moves; yet the spurs are so formed that they retain their grip on said window sash and do not fall out despite this oft-repeated movement.

It is highly desirable to have said device 17 remain indefinitely in position between said window sash 13 and jamb 14, and in order to further attain this end I preferably provide said spurs 19 and 22 in both ends of my device 17, although my invention is not necessarily limited to this particular construction.

20 Said side spurs 19 are purposely made longer than said intermediate spurs 22, to more surely overcome the effect of any side thrust of said window sash which otherwise might tend to force my device out of its position.

25 What I claim is:

1. An anti-rattler device for windows and the like comprising a bowed sheet spring with opposite edges at an end turned inward to provide

spurs, and with a slit intermediate said spurs with portions adjacent to such slit turned inward to form other spurs, all said spurs cooperative to hold the device from displacement with respect to a window sash.

2. An anti-rattler device for windows and the like comprising a bowed sheet spring with opposite side edges turned to project normally to said bowed sheet to provide spurs.

3. An anti-rattler device for windows and the like comprising a spring body portion bowing outwardly, two spurs at each end thereof at the outer side edges extending downwardly and being inset from the outer side edges of said body portion, said spurs extending in a substantially straight line from the point of beginning at said body portion to said ends, and two spurs at each end thereof at a point intermediate said spurs at said outer side edges spaced from each other and flaring outwardly from a common point of beginning in said body portion towards said end, said spurs at said outer side edge being longer than said spurs at said intermediate point, and of substantially the same depth throughout, the latter-mentioned spurs extending diagonally downward towards said end and being of greatest depth at the end of said device.

ELIO V. FRANCESCON.
